UNITED STATES PATENT OFFICE.

CARL C. R. CARLSON, OF DULUTH, MINNESOTA.

COAL CHUTE FOR CELLAR WINDOWS.

Application filed March 18, 1926. Serial No. 95,748.

The invention relates to chutes for cellar windows and has for its object the provision of a chute including a plate adapted to be pivotally mounted in a window casing and having flanges thereon to form the sides of the chute, the plate being adapted to form a closure for the window in one of its positions, provision being made for limiting the movement of the chute to open position comprising U-shaped members pivotally secured to the flanges, one of the ends of said U-shaped members being adapted to engage the top of the window casing when the chute is moved into open position, while the other ends of the U-shaped members have plates secured thereto forming a shield for the side of the building adjacent to the window to prevent marring the building when the chute is in use, stops being provided on the flanges to limit the movement of the U-shaped members when the chute is opened and closed.

The invention will be described in detail hereinafter and will be found illustrated in the accompanying drawings, in which—

Figure 1 is a front view of a window casing showing the chute in position and closing the window opening.

Figure 2 a vertical sectional view on a plane indicated by the line 2—2 of Figure 1, and

Figure 3 a view on a similar plane showing the chute in open position.

In the drawings similar reference characters will be used to designate corresponding parts in the several views.

The improved coal chute is shown in the drawings in position in a window casing A, B being strips on the inner side of the casing against which the plate 1 of the chute engages when in closed position as shown in Figures 1 and 2. Plate 1 is pivotally mounted in the sides of the window casing A as shown at 2, the sides of the casing being preferably formed with bayonet slots 3 to admit of removal and replacement of the chute in the casing. Side flanges 4 extend rearwardly of the plate 1 and together with said plate 1 form the chute for directing coal or other material through the window casing. Pivotally secured to each flange 4 is a U-shaped arm 5, and 6 is a stop on each

of the flanges that is adapted to engage said arms and hold them when the chute is in closed position as shown in Figure 2, so that 55 the ends 7 of the arms will engage the top of the window casing A and assumes the position shown in Figure 2 to limit the outward movement of the chute while the other ends of said arms 5, designated 8 are connected by a plate 9, that forms a shield for the side of the building above the window casing to prevent marring the building when dumping coal into the chute. The stops 6 are preferably formed removable so that 60 the arms 5 may assume an inverted position when it is desired to remove and replace the chute, it being clearly understood that the chute may be then swung downwardly outside of the window casing so that the pivot 70 2 may be removed from the bayonet slots 3, such removal being impossible when the chute is in operative position because of the flanges 4 engaging the strips B across the top of the window casing. 10 is a handle 75 for convenience in opening and closing the chute.

What is claimed is—

1. A coal chute for cellar windows, comprising a plate adapted to be pivotally secured in a window casing and engaging strips on said casing in closed position, flanges on said plate, U-shaped members pivotally secured to said flanges, one of the ends of said U-shaped members being adapted to engage the top of the window casing to hold the chute in open position, and a plate connecting the other ends of said U-shaped members and forming a shield.

2. A coal chute for cellar windows, comprising a plate adapted to be pivotally secured in a window casing and forming a closure therefor in one position, flanges on said plate, U-shaped arms pivotally secured to said flanges, one of the ends of said arms adapted to engage the top of the window casing to hold the chute in open position, a plate connecting the other ends of said U-shaped arms and forming a shield when the chute is open, and stops on said flanges and engaging said arms to limit their movements.

In testimony whereof I affix my signature,

CARL C. R. CARLSON,
